UNITED STATES PATENT OFFICE.

EDMUND H. WALKER, OF NEW YORK, N. Y.

DRAFT GEAR.

Application filed April 17, 1924. Serial No. 707,143.

To all whom it may concern:

Be it known that I, EDMUND H. WALKER, a citizen of the United States, residing at New York, in the county of New York and State of New York, have invented certain new and useful Improvements in Draft Gears, of which the following is a specification.

The invention relates to draft rigging for railway cars and more particularly to a draft rigging of the spring cushion type in which a plurality of springs is arranged in tandem and adapted to be simultaneously actuated whereby the combined capacities of all springs will be utilized to absorb the shocks and blows incident to service.

The primary object of my invention is to provide a tandem spring mechanism conforming in cross-sectional outline to friction mechanism and being so arranged as to fit within the standard draft rigging pocket and to cooperate with the carry iron provided for friction mechanism.

Another object of the invention is to provide a pair of counter-part spring casings having the wall portions and supplemental followers so arranged that upon the limit of compression of the springs the wall portions and the followers are all in intimate contact and form in effect a solid column extending from one main follower to the other to transmit excessive shocks above the capacity of the springs to the car underframe without detriment to the springs or to the parts of the cushioning mechanism.

With these and other objects in view, the invention consists in the various elements and combinations of elements hereinafter described.

In the drawings:

Figure 1 is a perspective view of one of the draft sills of a car showing the improved cushioning mechanism in position and illustrating the yoke, main followers, and coupler in normal position.

Figure 2 is a longitudinal cross-sectional view through the cushioning mechanism.

Figure 3 is a view in side elevation of one of the counter-part casings.

Figure 4 is a cross-sectional view on the line 4—5 of Figure 2 looking in the direction of the arrow adjacent the numeral 4.

Figure 5 is a cross-sectional view on the line 4—5 of Figure 2 looking in the direction of the arrow adjacent the numeral 5.

Figure 6 is a fragmentary top plan view

of the cushioning mechanism shown in Figure 1.

Figure 7 is an end elevational view of one of the counter-part casings, showing 60 the bifurcated end portion, and

Figures 8 and 9 are respectively, side elevation and end views of one of the supplemental followers.

Throughout the specification and drawing like parts are designated by like reference characters.

The numeral 1 designates the usual draft or center sill of the car underframe, it being of course understood that there is 70 a pair of sills between which the yoke, coupler and cushioning mechanism are disposed. Attached to the inner faces of the sills, in any convenient manner, is a front stop 2 and a rear stop 3, the vertical faces 75 of the co-acting pairs of which form the limits of the draft gear pocket. Within this pocket is disposed the cushioning mechanism comprising end or main followers 4—4, counter-part casings 5—5, and supplemental followers. The numeral 6 designates the usual type of friction draft rigging carry iron. The usual type of vertical yoke 7 is indicated by the reference numeral 7 and slidably connected to the 80 yoke in the usual manner by the key 8 is the coupler 9.

Since the casings 5 are identical, a description of one will suffice. The casing 5 is open at opposite ends and is substantially 90 circular in outline, being actually formed by a plurality of plane faces 10, 11, 12 and 13, each of which is arranged at an angle to the two adjacent faces. Adjacent one end the casing is provided with a bifurcated 95 portion 14 which may be formed by cutting away a portion of the opposite walls. Extending longitudinally of the casing and formed by the faces 12 and 13 are ribs 14, the purpose and object of which will be 100 hereinafter described.

Slidably mounted within the bifurcated portion of the casing 5 is a follower 15 having curved side faces 16 whose diameter is slightly less than the internal diameter 105 of the casing 5, which curved faces terminate in projecting portions 17—17 which conform to the adjacent wall section of the casing. It is to be observed that the portion 17 of the follower 15 is provided with faces 110 corresponding to the faces 10, 11, 12 and 13 of the casing. The follower 15 is preferably

cored for lightness and may be provided with a plurality of strengthening ribs 18 extending in one direction, which are connected adjacent their central portions by a rib 19 extending at right angles thereto.

The parts described are of course duplicated and these duplicate parts are assembled as follows: One of the casings 5 is rotated through an angle of 90° so that 10 the bifurcated portion of one casing is arranged at 90° to the bifurcated portion of the other casing. The followers 15 are then introduced into the respective casings and then a plurality of springs 20 is introduced 15 into each casing through the open end thereof and the casings so connected are then inserted between the main followers 4 and within the yoke 7. The springs 20 are preferably so arranged as to slightly exceed in 20 length the distance between the flat face of the follower 15 and the face of the adjacent follower 4 so that when the parts are assembled within the yoke the springs are placed under a slight initial compression.

25 It will be observed that by providing an octagonal shape the counterpart casings may be reinforced and strengthened without interference with clearance lines now held by the American Railroad Association as recommended practice. Since the counterpart casings are adapted to be inserted within the yoke with either casing in either position it necessarily follows that the casings cannot be reinforced and maintained as counterpart 30 ones unless the maximum diameter of each casing is within the width between the yoke arms. By providing a substantially octagonal shape it is possible to reinforce the corner portions, that is, along the meeting 35 edges of the casings, so that the cross sectional area of the casings measured at any point under maximum load is within the recommended practice of the American Railway Association. Not only does the reinforcing of the corners of the casing permit this highly desirable feature, but it also permits of augmented wearing surfaces 40 which of course prolong the life and usefulness of the cushioning unit. The octagonal 45 shape also permits the substitution of the counterpart casings for friction draft gear without the necessity of changing the carry 50 irons or their cooperating parts.

55 In the operation of the device, due to a movement of the coupler, one of the main followers 4 will approach the other. Such a movement will cause one of the casings 5 to move toward the other casing and since the adjacent ends of the casings are in engagement with the followers 15, respectively, it will be seen that each of said springs 20 will be compressed between one of the followers 4 and the adjacent followers 15. Should the force applied to the coupler exceed 60 the combined capacity of the springs 65

20 the followers 15 will be brought into engagement with the wall portions of the casings in which they are slideable, at which time the ribs 14 on the casings and the corresponding projections on the followers will 70 form in effect a plurality of columns extending from one follower 4 to the other and will form an exceedingly strong column to absorb the excessive force transmitted by the 75 coupler.

Having now described my invention, what I claim as new and desire to secure by Letters-Patent, is:

1. In a draft gear for railway cars, counterpart casings having slideable interfitting 80 telescoping engagement, a follower movable within each casing and actuated in one direction by the opposite casing, said followers each having projecting portions the surface contour of the projecting portions of 85 said followers and the cross sectional contour of said casings being octagonal in form.

2. In a draft gear for railway cars, counterpart casings having slideable interfitting 90 engagement and enclosing springs and followers, the casings having external faces at obtuse angles to one another, and means for longitudinally reinforcing said faces.

3. In a draft gear for railway cars, counterpart casings having slideable interfitting 95 engagement and enclosing springs and followers, the casings having external faces at obtuse angles to one another.

4. In a draft gear for railway cars, counterpart casings having slideable interfitting 100 engagement and enclosing springs and followers, the casings having external faces at obtuse angles to one another, certain of the faces being provided with longitudinal 105 strain transmitting ribs.

5. In a draft gear for railway cars, counterpart casings having slideable interfitting 110 engagement and enclosing springs and followers, the casings having external faces at obtuse angles to one another, alternate ones 110 of the faces being formed with longitudinal strain transmitting ribs.

6. In a draft gear, springs arranged in tandem, followers at the outer ends of the springs, followers at the adjacent ends of 115 the springs, and counterpart casings surrounding and enclosing the springs, said casings having their adjacent ends slotted and slideably interfitting, with portions of the second named followers fitting within 120 the slots, the casings having their outer peripheries of polylateral formation with obtuse angles and being provided at the edges of the slots with longitudinal thickened portions constituting strain transmitting ribs. 125

7. In a draft gear, springs arranged in tandem, followers at the outer ends of the springs, followers at the adjacent ends of the springs, and counterpart casings surrounding 130 and enclosing the springs, said casings

having their adjacent ends slotted and slidably interfitting, with portions of the second named followers fitting within the slots, the casings having their outer peripheries of 5 poly lateral formation with obtuse angles, and the edges of the slots being located at the centers of alternate ones of said faces.

8. In a draft gear, counterpart casings having slotted and slidably interfitting ends, 10 followers at the outer ends of the casings,

springs within the casings engaging the followers, and followers within the casings in engagement with the inner ends of the springs, said last named followers having extensions slidably engaged within the slots, ¹⁵ and further having their confronting faces formed with intersecting stiffening ribs.

In testimony whereof I affix my signature.

EDMUND H. WALKER.
